DESIGN.

J. L. FOLSOM.

CARPET.

No. 15,430.

Patented Oct. 7, 1884.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 15,430, dated October 7, 1884.

Application filed August 6, 1884. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The design is characterized by scattered and

irregular leaf groups having inconspicuous stem-connections and lichen-like sprays. Small star-shaped flowers are found in some of the groups.

The design is clearly shown in the accompanying photograph.

I claim—

The design for a carpet, consisting of the scattered leaf and flower groups with lichen-like sprays, substantially as shown and described.

JAS. L. FOLSOM.
